CLAIM

The ornamental design for an ice skate, as shown and described.

DESCRIPTION

FIG. 1 is a front left perspective view of an ice skate showing our new design;

FIG. 2 is a left rear perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a rear view thereof.

The broken line showing of various regions is for illustrative purposes only and forms no part of the claimed design.
